UNITED STATES PATENT OFFICE.

CARL BÖHME, OF SAN FRANCISCO, CALIFORNIA.

OIL-BURNER TIP.

1,007,325.

Specification of Letters Patent. Patented Oct. 31, 1911.

Application filed May 16, 1911. Serial No. 627,503.

To all whom it may concern:

Be it known that I, CARL BÖHME, a subject of the Emperor of Germany, residing in the city and county of San Francisco and 5 State of California, have invented new and useful Improvements in Oil-Burner Tips, of which the following is a specification.

This invention relates to tips, and particularly for an improved tip for oil burn-10 ers.

The object of the present invention is to provide a substantial, durable, integral tip of special design, and so formed as to produce a peculiarly shaped tongue of flame; 15 and to provide a burner involving special details of formation with a purpose of enhancing the mixture of the combustible fuel issuing from the burner.

The invention consists of the parts, and 20 the construction and combination of parts, as hereinafter more fully described and claimed, having reference to the accompanying drawings, in which—

Figure 1 is a perspective view of a burner 25 tip. Fig. 2 is a longitudinal, central section, through the burner tip. Fig. 3 is a section transversely through the burner and its orifice. Fig. 4 shows a similar section of a burner tip having a different orifice.

30 The purpose of the present invention is to devise a discharge tip adapted to be attached to various forms of oil burners, a part of one being indicated in dotted lines at 2. The tip is illustrated in the perspective view, 35 Fig. 1, as having an internally threaded stem 3 and a transverse face 4, which may be rectangular in plan view, and is preferably in the form of a segment in side view.

The efficiency of the present tip is derived 40 from the peculiar formation of the fuel discharging orifice 5, which is formed longitudinally in the face 4, and which communicates with the interior 6 of the tip. As shown in Fig. 2, the interior is provided 45 with a hemispherically curved end portion 6', terminating comparatively close to the plane of the face 4, and expands conically in the stem 3.

In forming the discharge orifice 5 in the 50 face 4, a suitable tool is used which will longitudinally channel the face 4 of the tip, and form an opening or slot having a curved

bottom surface; the orifice 5 being cut sufficiently deep to intersect the curved portion 6' within the tip, that is, I form a cut 55 longitudinally across the face 4 of the tip, the arc of the cut intersecting and overlapping a portion of the arc of the chamber 6' in a plane approximately the center of the tip. This peculiar relation of the external opening or orifice 5 and the chamber 6' forms acute, sharp cutting edges at the points *a* of intersection, Fig. 2.

I have found by actual practice with tips constructed in this manner that an extremely efficient mixture of the fluids issuing from the chamber 6' is obtained; and that by varying the radius of the orifice 5 a different shaped tongue of flame is produced; and also by varying the width of the 70 orifice 5 a different shaped tongue of flame is produced. If it is necessary to have a tip which must produce a comparatively long tongue-like flame, the orifice 5 is cut wider and the arc of the cut is of comparatively 75 small radius. If a very flaring or fan-shaped flame is to be produced, due to the peculiar construction of the fire-box in which the tip is being used, then the orifice 5 is formed with an arc of considerably 80 greater radius and this produces the desired fan-shaped flame as the fuel issues from the tip.

Having thus described my invention, what I claim and desire to secure by Letters 85 Patent, is—

A tip for oil burners comprising a stem and a head extending transversely and at one end of the stem, the stem having a bore threaded at one end and tapering toward 90 its other end and terminating in a hemispherically curved portion adjacent the plane of the outer face of said head, and said head having a longitudinal slot, the base of which is curved and intersects the 95 said curved portion of the stem bore, forming acute edges at the points of intersection.

In testimony whereof I have hereunto set my hand in the presence of two subscribing witnesses.

CARL BÖHME.
